UNITED STATES PATENT OFFICE.

FRANK H. WARREN, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

INSEAM SHOE-SEWING MACHINE.

1,154,554.

Specification of Letters Patent. Patented Sept. 21, 1915.

Application filed January 9, 1913. Serial No. 740,945.

To all whom it may concern:

Be it known that I, FRANK H. WARREN, a citizen of the United States, residing at Swampscott, in the county of Essex and 5 State of Massachusetts, have invented certain new and useful Improvements in Inseam Shoe-Sewing Machines; and I do hereby declare the following to be a full, clear, and exact description of the invention, such 10 as will enable others skilled in the art to which it appertains to make and use the same.

The present invention relates to inseam shoe sewing machines, and more particularly 15 to a shoe sewing machine provided with tack pulling devices.

When a welt or a turn shoe is lasted, the upper is held by means of tacks which are driven through the edge of the upper and 20 through the sole into a wooden last. After the shoe is lasted, it is presented to a sewing machine which sews a seam of stitches uniting the upper to the sole. During the sewing 25 operation, it frequently happens that the needle strikes a tack and breaks. It is, therefore, desirable that the tacks be pulled or lifted out of the path of the needle, or else pulled enough to loosen them so that they are deflected to one side by the needle 30 in case they are struck by the needle, and do not offer sufficient resistance to break it.

With the object, therefore, of pulling the tacks so that the sewing machine needle will not be broken by the tacks, the present invention contemplates an inseam shoe sewing 35 machine which is provided with a tack puller which operates to pull the tacks which are in the path of the needle.

The present invention in one of its narrower aspects relates to a tack puller which is mounted to move with the back gage slide of the shoe sewing machine known to the trade as the Goodyear welt and turn machine, so that this machine may operate to 45 pull the tacks from the shoes which are sewed by it.

In the drawings, which illustrate the preferred embodiment of the present invention, Figure 1 is a side view of part of a Goodyear 50 welt and turn machine showing the needle, the feed point, a section of a lasted shoe, and the tack pulling mechanism; and Fig. 2 is a detail view of the tack pulling mechanism.

The present invention is particularly applicable to machines for operating upon 55 turn shoes and is therefore illustrated in connection with the Goodyear welt and turn machine when the back gage slide is provided with the back gage which is used for turn work. The Goodyear welt and turn 60 machine to which the present invention is applied, is illustrated with substantial accuracy in the patent to French and Meyer, No. 412,704, dated October 8, 1889. In this machine, the thread is drawn through the 65 work by a curved hook needle 1 which penetrates the upper 2 and the between substance 3 of the sole 4 of the lasted shoe, and sews a seam of chain stitches uniting the upper to the sole. The work is fed by means of a 70 feed point or awl 5 while the needle is out of the work. During the feed, the back gage slide 10 is retracted to permit the shoe to be more easily fed. After the work is fed and before the needle again enters the work, 75 the back gage slide is spring-pressed forwardly to bring the back gage 11 against the shoe. Then the needle 1 descends and penetrates the work.

In the illustrated embodiment of the present invention, a tack puller or tack pulling tool 15 is pivotally mounted, by means of a screw stud 16, upon a plate 17 which is mounted upon the right hand side of the back gage 11. The plate 17 has a slot in 80 which is engaged a feather 18 on the side of the back gage. A longitudinal adjustment between the tack puller 15 and the back gage is secured by means of the elongated slot 19 in the plate 17 through which is received 85 the screw 20 which secures the plate 17 to the back gage. The end of the tack pulling tool 15 has a tack engaging claw 25 which is pushed under the heads of the lasting tacks and pulls them. When the back gage 11 90 and its slide 10 move forwardly during the cycle of stitch forming operations, the claw 25 comes in contact with the lasting tacks 26 which may be in its path of movement. The continued forward movement of the 95 slide 10, which takes place before the back gage 11 is brought against the work, causes the inclined lower face 27 of the tack pulling tool 15 to ride up and over the shoe and act after the manner of a cam to deflect the 100 tack pulling tool 15 and cause it to turn 105

about its fulcrum 16 and raise its forward end to lift the tack which is engaged by the claw 25. The movement of the claw 25 after it engages the head of the tack is both forward and upward, so that it both bends the tack away from the needle and loosens it. If the tacks are entirely withdrawn from the shoe they are not only scattered about the sewing machine but are also liable to become lodged in the channel of the sole and to remain there when the shoe is completed. Therefore, the tack puller is preferably adjusted so that the tacks are only partially withdrawn from the shoe. The partially withdrawn tacks are sufficiently pulled or loosened so that they present no obstacle to the needle. The tack pulling claw 25 is located at the right of the back gage 11 (as viewed from the front of the machine) and at the right of the needle 1. The shoe is fed from right to left and consequently the tack pulling tool is located on the side of the needle from which the work is fed and operates upon the shoe in advance of the needle to loosen the tacks in the shoe just before it is fed to the needle. The complete tack lifting operation is therefore completed before the needle has any opportunity to strike the tack. Moreover, the tack pulling tool by virtue of its position at one side of the needle path operates without interfering in any way with the usual construction and operation of the needle 1 or the needle guide 6.

After the needle has entered the work and drawn back its loop of thread, the back gage slide and the back gage are retracted from the work and the work is fed. In order that the tack pulling tool shall not interfere with the feeding movement of the shoe, mechanism is provided for holding the tack pulling tool in its raised or deflated position until the back gage slide is fully retracted. This holding mechanism comprises a pawl 30 pivotally mounted by means of a screw stud 31 upon the rear end of the plate 17, and normally held in engagement with ratchet teeth 32 on the rear of the tack pulling tool 15 by means of the standing rear portion 33 of a leaf-spring 34 which is secured to the plate 17 by means of a screw 35. When the forward end of the tack pulling tool 15 is raised by contact with the shoe, the pawl 30 operates to hold the forward end of the tack pulling tool in its raised position. When the slide 10 has nearly reached the backward limit of its movement and the tack pulling tool is therefore so far retracted from the work as not to interfere with the feed, the pawl 30 is released by means of an adjustable stop 40 against which the upper end of the pawl 30 is brought. The stop 40 is adjustably mounted by means of a screw 41 and slot 42 connection so that the time of tripping the

pawl may be varied. The screw 41 is threaded in a block 43 which in turn is held by means of a screw 44 upon a part 45 of the frame of the machine. After the tack pulling tool is released by the pawl 30, its forward end is turned downward by means of the pressure of the forward end 50 of the spring 34 which bears against the top of the tack pulling tool. The movement of the tack pulling tool under the action of the spring 34 is limited by means of a screw 51 which is loosely received in a curved slot 52 in the tack pulling tool. 75

The operation of the machine is briefly as follows: After the shoe has been fed, the back gage 11 is moved forward by the spring of the back gage slide and carries with it the tack pulling tool 15, the claw 25 of which engages beneath the head of the tack 26 before the back gage 11 is brought into engagement with the shoe. After the tack pulling claw 25 has engaged the tack, the back gage continues its forward movement under the action of the spring of the back gage slide and the tack pulling tool 15 rides over the shoe and its claw 25 is moved forwardly and upwardly over the shoe to pull the tack 26. The needle then descends and penetrates the work and draws back its loop of thread. After the needle is retracted, the back gage slide 10 together with the back gage 11 and tack pulling tool 15 are retracted backward away from the work. During the first part of this backward movement, the claw 25 of the tack pulling tool is held above the shoe by means of the pawl 30, so that it does not interfere with the feeding movement of the shoe. When the back gage slide 10 has nearly reached the limit of its backward movement, the pawl 30 is tripped and allows the claw of the tack pulling tool to be returned into position to again operate when the back gage again moves against the shoe. 100

While the preferred embodiment of the present invention has been specifically illustrated and described, and has been particularly explained with reference to the Goodyear welt and turn machine, it is to be understood that the present invention is not limited to its preferred embodiment or to its use in connection with the Goodyear machine, but may be embodied in other constructions of tack pullers and may be applied to other shoe sewing machines 115 within the scope of the invention as set forth in the following claims. 120

1. An inseam shoe sewing machine having, in combination, stitch forming devices including a curved hook needle, means for feeding the work, a tack pulling tool, mechanism operating to bring the tack pulling tool into engagement with a tack and against the shoe, said tack pulling tool when brought against the shoe being deflected by 125

- the shoe and operating when so deflected to pull the tack, means for holding the tack pulling tool in its deflected position when the shoe is fed, and means acting automatically to release said holding means before the tack pulling tool is again moved toward the shoe. 70
2. An inseam shoe sewing machine having, in combination, stitch forming devices including a curved hook needle, means for feeding the work, a back gage, a back gage slide moved toward and from the work during the cycle of stitch forming operations, a tack pulling tool pivotally supported by the back gage slide and having an inclined work engaging surface which slides over the shoe when the slide is moved toward the shoe and deflects the tack pulling tool and causes it to pull a tack from the shoe, and a device for holding the tack pulling tool in its deflected position when the shoe is fed. 75
3. An inseam shoe sewing machine having, in combination, stitch forming devices including a curved hook needle, a tack puller, mechanism operating to bring the tack puller into engagement with a tack, and means operated by contact with the shoe for moving the tack puller to pull the tack. 80
4. An inseam shoe sewing machine having, in combination, stitch forming devices including a curved hook needle, a back gage slide moved toward and from the work during each cycle of stitch forming operations, and a tack pulling tool supported by the back gage slide and having an inclined work engaging surface which slides over the shoe when the slide is moved toward the shoe and deflects the tack pulling tool and causes it to pull a tack from the shoe. 85
5. An inseam shoe sewing machine having, in combination, stitch forming devices including a curved hook needle, a back gage moved toward and from the work during each cycle of stitch forming operations, a tack puller mounted on the back gage, and means operated by contact with the shoe for moving the tack puller with relation to the back gage to pull tacks. 90
6. An inseam shoe sewing machine having, in combination, stitch forming devices including a curved hook needle, means for feeding the shoe, a tack pulling tool, mechanism operating to bring the tack pulling tool into engagement with a tack and against the shoe, said tack pulling tool when brought against the shoe being deflected by the shoe and operating when so deflected to pull the tack, and means for holding the tack pulling tool in its deflected position when the shoe is fed. 95
7. An inseam shoe sewing machine having, in combination, stitch forming devices including a curved hook needle, means for feeding the shoe, a tack puller located on the side of the needle from which the work is fed and operating upon the shoe before it is fed to the needle, and means for actuating the tack puller to only partially withdraw tacks from the shoe. 100
8. An inseam shoe sewing machine having, in combination, stitch forming devices including a curved hook needle, a back gage slide moved toward and from the work during each cycle of stitch forming operations, and a tack puller supported by the back gage slide and operating when the slide is moved toward the shoe to engage and pull a tack from the shoe. 105
9. An inseam shoe sewing machine having, in combination, stitch forming devices including a curved hook needle, a tack pulling tool, and mechanism operating to bring the tack pulling tool into engagement with a tack and against the shoe, said tack pulling tool when brought against the shoe being deflected by the shoe and operating when so deflected to partially withdraw the tack from the shoe. 110
10. An inseam shoe sewing machine having, in combination, stitch forming devices including a curved hook needle, a back gage, and a tack puller pivotally mounted on the back gage. 115
11. An inseam shoe sewing machine having, in combination, stitch forming devices including a curved hook needle, means for feeding the shoe, a tack pulling tool, and means operating independently of the movement of the needle for advancing the tack pulling tool toward the shoe and causing it to engage and only partially withdraw a tack from the shoe. 120
12. An inseam shoe sewing machine having, in combination, stitch forming devices including a curved hook needle, a back gage slide moved toward and from the work during each cycle of stitch forming operations, and a tack puller supported by the back gage slide. 125
13. An inseam shoe sewing machine having, in combination, stitch forming devices including a curved hook needle, a tack pulling tool, and mechanism operating to bring the tack pulling tool into engagement with a tack and against the shoe, said tack pulling tool when brought against the shoe being deflected by the shoe and operating when so deflected to pull the tack. 130

it to pull a tack from the shoe, a spring acting to hold the tool against the shoe, a pawl and ratchet device for holding the tool in its deflected position when the shoe is fed, 5 and means acting automatically to release the pawl and ratchet device when the slide is moved away from the shoe and allow the

spring to return the tack pulling tool to its original position.
